UNITED STATES PATENT OFFICE.

AMOS DAVELER, OF STERLING, ILLINOIS, ASSIGNOR TO EUREKA COMPANY, OF ROCK FALLS, ILLINOIS.

CASKET-CLAMP FOR HEARSE.

1,262,650.

Specification of Letters Patent. Patented Apr. 16, 1918.

Application filed April 27, 1917. Serial No. 164,914.

To all whom it may concern:

Be it known that I, AMOS DAVELER, a citizen of the United States, residing at Sterling, in the county of Whiteside and State of Illinois, have invented certain new and useful Improvements in Casket-Clamps for Hearses, of which the following is a specification.

My invention pertains to casket clamps for hearses and funeral cars, of that kind which engage the sides of the casket as it rests on the table of the hearse, to hold the same in position while being transported. One of the purposes thereof is to do away with the slots which are commonly found in hearse tables, in which the clamping members are movable toward the casket or away therefrom. The device is simple in construction, can be easily operated, and the operating parts thereof are all concealed beneath the table. The clamping members are so disposed that when they are in engagement with a casket any tendency thereof to move rearwardly only operates to tighten the grip of the clamps.

In the drawings; Figure 1 is an inverted plan view of the hearse table and mechanism connected therewith. Fig. 2 is a top plan view of a hearse table equipped with my device. Fig. 3 is a side view thereof. Fig. 4 is an edge view of one of the shoes 20.

1 represents the table of a hearse, upon which it is usual to support a casket, such table being provided, near the edge thereof, with two pairs of arms 2, pivoted so as to swing in a horizontal plane. The pivots 3 of such arms extend through the table, and are provided on the lower side thereof with arms 4 and 5. A screw 6 is rotatably mounted in a cross-piece 7 and bearing 8 on the lower face of the table, and longitudinally movable on such screw is a traveler 9, pivotally connected with which is a pair of bars 10, pivoted at their outer ends to the inner ends of the arms 4. A movement of the traveler 9 toward the rear end of the table, which is at the right, draws the arms 4 in the same direction, and moves the free ends of the arms 2 inwardly, bringing the same in contact with the casket, if one be supported on the table 1, and, as the movement of the traveler continues, gripping the casket tightly between such arms.

The traveler 9 is also connected with a slide-bar 11, which passes under the cross-

bar 7 and a similar bar 12, and is guided at the rear end of the table by pieces 13 and at the forward end by guides 14. Bars, 15, similar to the bars 10, are pivotally connected with the slide-bar 11, such bars also having a pivotal connection with the arms 5. Any movement of the traveler 9 and arms 4 is thereby accompanied by a corresponding action of the arms 5, causing the inner pair of arms 2 to move inwardly or outwardly simultaneously with the other pair thereof. The sides of a casket are thus engaged by both pairs of arms 2 at the same time, and by reversing the movement of the screw 6 the same can be simultaneously released.

The screw 6 is provided with a rearward extension 16, provided in its end with a pin 17, adapted to be engaged by recesses in the end of a sleeve 18, slidable on the extension 16, and provided with a crank 19, for use in rotating the same. The sleeve and crank are normally out of the way beneath the table, as shown in Fig. 1, but when it is desired to operate the screw the sleeve 18 is moved outwardly to the end of the extension 16, as shown in Fig. 2, in which position the pin 17 is engaged by the recesses in the end of the sleeve 18. The rotation of the sleeve is thus imparted to the screw 6, to suitably operate the same.

The free ends of the arms 2 are preferably provided with shoes 20, pivoted thereto so as to adapt themselves to the sides of the casket. Said arms are preferably located at such a height above the table that they will engage the base of the casket, and one of said shoes is shown in Fig. 4 provided with a concave face, to enable the same to more closely engage the molding at the bottom of the casket.

The arms 2 are disposed toward the inner end of the hearse, as shown in Figs. 2 and 3, and when such arms, with the shoes thereon, are clamped tightly against the casket, any tendency of the casket to move rearwardly in the hearse causes the shoes to more tightly grip the same, the tendency being to move the ends of the arms 2 closer together.

Each of the clamping arms 2, with the accompanying pivot and operating arm therefor, constitutes in effect a bell-crank lever, one of the arms of such lever, to which the power is applied, being below the table, and

the opposite arm, to which the power is communicated, being above the same.

What I claim as my invention, and desire to secure by Letters Patent of the United States, is:

1. In a device of the class described, in combination with the table of a hearse, two pairs of arms pivotally mounted so as to move horizontally above said table; screw mechanism on the lower side of said table operatively connected with one of said pairs of arms, to move the free ends thereof inwardly or outwardly, as desired, and means for imparting the movement of said screw mechanism to said second pair of arms, to move the same coincidently with said first named pair.

2. In a device of the class described, the combination, with the table of a hearse, of a bell-crank lever pivoted near the edge thereof, one of the arms of said lever being above the table and the other arm thereof beneath said table; and screw devices below said table, operatively connected with that 25 arm of said lever adjacent thereto, so as to move the free end of the upper arm of said lever inwardly or outwardly, as desired.

3. In a device of the class described, in combination with the table of a hearse, a pair of levers, mounted in said table, so as to move horizontally, each of said levers comprising an arm above said table and an arm below said table at a different angle from said first-named arm, said arms being united by a pivot which forms a fulcrum therefor; a screw mechanism rotatably mounted beneath said table; and a traveler operable by said screw mechanism and operatively connected with the lower arms of 40 said levers, to impart to the upper arms thereof a desired inward or outward movement.

4. In a device of the class described, the combination with the table of a hearse, of two pairs of arms pivotally mounted on the upper face thereof, and provided at their free ends with jointed shoes conforming to the surface of the body to be engaged thereby; and screw mechanism on the under side 50 of said table, operatively connected with the pivots of said arms, to move the free ends thereof inwardly or outwardly, as desired.

5. In a device of the class described, in

combination with the table of a hearse, two pairs of arms pivotally mounted on the upper face of said table, and provided beneath said table with inwardly extending operating arms; screw mechanism beneath said table in proximity to one of said pairs of arms; a traveler operable by said screw mechanism and operatively connected with one of said pairs of arms beneath said table; and a slide-bar connected with said traveler, and operatively connected with the other pair of arms beneath said table, whereby the arms above said table are simultaneously operated.

6. In a device of the class described, in combination with the table of a hearse, two pairs of arms pivotally mounted therein, so as to move in a horizontal plane, and provided at their free ends with casket engaging means, said arms being disposed toward the inner end of said table; and screw mechanism beneath said table, operatively connected with the pivots of said arms, so as to cause the simultaneous movement thereof inwardly or outwardly.

7. In a device of the class described, in combination with the table of a hearse, two pairs of arms pivotally mounted on the upper face of said hearse, so as to swing in a horizontal plane; operating arms beneath said table, connected with the pivots of said first-named arms; a screw rotatably mounted beneath said table; a traveler movable longitudinally of said screw and operatively connected with said operating arms, to move said first-named arms simultaneously inwardly or outwardly; a shaft forming an extension of said screw, projecting beyond the outer end of said table and provided with engaging means at its outer end; and a sleeve slidable on said shaft, having an operating handle attached thereto, and provided with means for coöperating with the engaging means on the end of said shaft, to cause said shaft and sleeve to rotate together.

In testimony whereof I affix my signature in the presence of two witnesses.

AMOS DAVELER.
